UNITED STATES PATENT OFFICE.

GEORGE W. FOUBE, OF SACRAMENTO, CALIFORNIA, ASSIGNOR TO CALKY COMPANY, OF CHICAGO, ILLINOIS, A CORPORATION OF ILLINOIS.

RECEDING TIMER CAM.

Application filed March 29, 1922, Serial No. 547,898. Renewed June 25, 1925.

To all whom it may concern:

Be it known that I, GEORGE W. FOUBE, a citizen of the United States, residing at the city of Sacramento, county of Sacramento, 5 and State of California, have invented new and useful Improvements in Receding Timer Cams, of which the following is a specification.

This invention relates to an electric ignition system for internal combustion engines, 10 and especially to a cam whereby the circuit making and breaking mechanism is actuated.

Practically all internal combustion engines employing electric ignition require a 15 making and breaking mechanism and a co-operating mechanism to either retard or advance the spark. The circuit making and breaking mechanism is in practically all instances actuated by a cam fixed on a rotary 20 shaft positively driven from the engine crank shaft, and as such is the case it can readily be seen that the ignition circuit will be actuated whether the engine rotates ahead or reverse. It however happens that most 25 engines of this character are designed to rotate in one direction only and are for this reason usually detrimentally affected by a reversal, particularly when caused by backfiring, due to an advanced spark. Where a 30 hand crank is employed for starting purposes, backfiring, caused by an advanced spark, is often disastrous, both to life and limb and any number of cases could be cited where arms have been broken and serious 35 injuries received. The object of the present invention is to generally overcome the objections and dangers above mentioned; to improve and simplify the circuit making and breaking actuating mechanism, and particularly to provide a receding form of cam 40 whereby backfiring and reversal of the engine may be entirely prevented regardless of whether the spark is advanced or retarded. Further objects will hereinafter appear.

45 The invention consists of the parts and the construction, combination and arrangement of parts as hereinafter more fully described, and claimed, having reference to the accompanying drawings, in which—

50 Fig. 1 is a plan view of an electric circuit making and breaking mechanism, showing the application of the invention.

Fig. 2 is a cross section of the rotor and the cam carried thereby.

Fig. 3 is a perspective view of the rotor 55 showing the cam removed.

Fig. 4 is a perspective view of the cam.

Referring to the drawings in detail, and particularly to Fig. 1, A indicates a casing of suitable shape and construction, and 2 and 60 3 a pair of contacts supported thereby. The contact 2 is in this instance stationary as shown and insulated from the casing, while the contact 3 is supported by a spring arm 4, also secured to the casing as indicated at 5 65 and insulated therefrom. Journalled centrally of the casing and disposed directly below the spring arm 4 is a shaft 6, and keyed or otherwise secured thereon, as indicated at 7, is a rotor 8. Formed in the periphery of 70 the rotor is a recess 9, and slidably mounted in said recess is a cam member generally indicated at 10. The bottom of the recess presents a flat sliding surface, as at 11, and the lower face of the cam is similarly flat, as at 75 12. The inner end of this face is however slightly deflected or curved, as at 13, to form a rocking point, hereinafter to be described, while the forward end of the cam terminates in a hook shaped portion 14, which normally engages a notch or recess 15 formed in the outer face of the rotor. The cam proper, as indicated at 16, which engages with and actuates the spring arm 4, projects beyond the periphery of the rotor when the 85 shaft 6 rotates in a normal direction, but if the motor and the shaft 6 driven thereby are accidentally or otherwise reversed, the cam will recede and the spring arm 4 will be actuated. This is accomplished, due to the 90 fact that the cam as a whole will recede within the recess 9 and thus avoid engagement with the spring arm 4, that is such engagement as will lift the arm and close the 95 contacts 2 and 3. The receding movement of the cam is limited by a recess 16 formed in the upper face of the cam, said recess terminating in a pair of opposed shoulders 17 and 18, which are adapted to engage a pin 19 supported in the opposite side walls of the 100 recess 11. The cam is normally held in its projected position, as shown in Figs. 1 and 2, by a spring 20. This spring is secured at its lower end, as at 21, in a slot or recess 22 formed in the face of the rotor at approximately right angles to the sliding surface 11 105 formed in the recess 9. The upper end of the spring engages the rear end of the cam

and exerts a sufficient tension to normally hold it projected; the projected position being limited by engagement of the shoulder 18 with pin 19, the receding movement of the 5 cam being similarly limited by engagement of shoulder 17 with the pin 19.

The normal direction of rotation is that indicated by the arrow in Fig. 1. During such rotation cam 16 will engage the lower 10 face of the spring arm 4 and will thus raise the same a sufficient distance to close a circuit between the contacts 2 and 3. However if the direction of rotation is reversed accidentally or otherwise, sufficient movement to close contacts 2 and 3 will not be 15 obtained. This is due to the fact that the rear side of the cam indicated at 25 would then first engage the spring arm and a tilting movement would be imparted to the 20 cam about the rear rocker face 13, which would lift the hook portion 14 out of engagement with the notch 15 and the dotted line position shown at 26 would then be assumed. Further movement of the rotor 25 would cause the cam to move inwardly in the recess 9 against the tension of the spring 20 and it would thus entirely recede with relation to the outer surface or periphery of the rotor, thereby preventing closing of 30 the contacts 2 and 3 and as no spark would be formed, continued rotation of the engine or motor would be prevented. The moment the cam passes engaging position with relation to arm 4, pressure on the spring 20 35 would again project the cam and engagement of the hook 14 with the notch 15 would be made, thus retaining the cam in its projected position until engagement with arm 4 will be lifted and if the direction of rotation is reversed, recession of the cam will 40 take place. This action of the cam is exceedingly important; first, it can be seen that it is possible to considerably advance the spark before starting without any danger of backfiring or reversing the normal 45 direction of rotation; danger to life and limb is thus avoided; second, detrimental effects, such as backfiring into the carburetor and otherwise are also avoided; third, 50 a rotor and cam constructed as here shown can be employed in connection with practically any type of circuit making and breaking mechanism, and as such may be installed or applied to standard makes of mechanism 55 of this character.

While certain features of the present invention are more or less specifically illustrated, I wish it understood that various 60 changes in form and proportion may be resorted to within the scope of the appended claims, similarly that the materials and finish of the several parts employed may be such as the experience and judgment of the manufacturer may dictate or various 65 uses may demand.

Having thus described my invention, what I claim and desire to secure by Letters Patent is—

1. In a device of the character described, a circuit making and breaking actuating mechanism, comprising a rotor, normally turnable in one direction only, a cam member carried by the rotor and normally projecting beyond the periphery thereof, means permitting a predetermined sliding movement of the cam with relation to the rotor upon reversal of the rotor to permit recession of the cam, and a spring for automatically projecting the cam a predetermined distance. 70

2. In a device of the character described a circuit making and breaking actuating mechanism, comprising a rotor normally turnable in one direction only, a recess formed in the face of the rotor, a cam member slidably mounted in said recess, said cam normally projecting beyond the periphery of the rotor when in one position and being movable within the periphery of the 75 rotor when in another position, and means 80 for normally maintaining the cam in projected position, said means also permitting recession of the cam within the periphery of the recess during reversal of the 85 rotor. 90

3. In a device of the character described a rotor, a recess formed in the outer face thereof, a cam member slidably mounted in said recess and normally projecting beyond the periphery of the rotor, a spring engaging one end of the cam and normally maintaining it projected, a hook like member on the opposite end of the cam, a shoulder on the rotor with which the hook like member engages, a recess terminating in stop shoulders formed on the outer face of the cam member, and a pin carried by the rotor engageable with said shoulders to limit the 100 sliding movement of the cam. 105

4. In a device of the character described a rotor, a recess formed in the outer face thereof, a cam member slidably mounted in said recess and normally projecting beyond the periphery of the rotor, a spring engaging one end of the cam and normally maintaining it projected, a hook like member on the opposite end of the cam, a shoulder on the rotor with which the hook like member engages, a recess terminating in stop shoulders formed on the outer face of the 110 cam member, a pin carried by the rotor engageable with said shoulders to limit the sliding movement of the cam, and means 115 permitting a slight rocking movement of the cam with relation to the recess to disengage the hook portion on the cam with relation to the shoulder in the rotor. 120 125

GEORGE W. FOUKE.
